tion of Delaware

Application December 30, 1933, Serial No. 704,605

21 Claims. (Cl. 274—5)

This invention relates to phonographic apparatus, and more particularly to sound recording and sound reproducing apparatus of the type employing a photographic disc whereon the sound is recorded in the form of an uninterrupted spiral.

Of the phonographic systems employed in the prior art, there are two types which have been preferred over others. According to one of these, the sound is recorded by cutting, etching, embossing, pressing, etc., a sound groove into a solid medium from which, or from a duplicate of which, the sound is reproduced by tracking the sound groove with a stylus or needle. This system is subject to the serious disadvantages that both the records and needles employed suffer considerable wear which renders them unfit for further use after a comparatively short life and the further disadvantage that the drag of the needle over the record introduces foreign noises which are objectionable.

According to the other system, the sound is recorded photographically, most generally upon a long strip of sensitized film which, during reproduction, is run through the reproducing apparatus from one reel onto another. While this system is free from some of the disadvantages of the first system, it is, nevertheless, subject to some that are just as serious as those above noted. For example, a film phonograph, regardless of its simplicity, has an element of complexity about its threading. Moreover, such a phonograph includes a multiplicity of parts such as a film guide or support at the reproducing station, pressure rollers, film reels, etc. As for the film itself, it must constantly be wound on and unwound from the reels and, being usually fed by sprockets the teeth of which engage the sprocket hole perforations, is subject to great wear and tearing, the latter necessitating patching, splicing, etc. and involving considerable servicing. Another disadvantage of this system is that the film is subject to scratching and marring during handling and during passage through the reproducer, all of which introduce obnoxious foreign noises. Also, the duplication of records from long films necessitates complicated machinery and processing, and all of the foregoing have in no small way mitigated against the universal adoption of the photographic system of recording and reproducing sound.

In order to eliminate some of the difficulties noted above, it has been proposed to record the sound photographically, in the form of an uninterrupted spiral, upon a sensitized circular disc or plate. So far as I am aware, however,

prior art systems of this type have employed complicated devices for scanning the sound track. For example, lead screws and the like have been employed to move the optical system, light source, and photoelectric device used in reproduction 5 radially across the record. Not only is a construction of this sort cumbersome, but it is difficult to set up and control accurately. Also, with such set-ups of the prior art, it is extremely difficult, if not altogether impossible, to make provision for the continued repetition of a record or any preselected portions thereof, or for the reproduction of one record and the immediate reproduction of a second, and perhaps unrelated, record, with an immediate return to the first 10 record or to another record upon completion of the second one, as might be required in special uses of the phonograph, such as in advertising, 15 announcing, etc. Where, as in a few cases, repeat mechanisms may have been provided, they have 20 been both complicated and expensive.

The primary object of my invention is to provide a photophonographic apparatus of the disc type which will be free from the disadvantages of the prior art and which is so constructed and 25 arranged that it will be flexible in its uses and will, therefore, meet practically every reasonable requirement of sound reproducing apparatus.

Another object of my invention is to provide 30 an improved apparatus of this type which will include a minimum number of movable parts and which will, therefore, be free from unusual and unnecessary wear.

Still another object of my invention is to provide 35 an improved apparatus of the type noted which can be set to repeat any preselected portions of a record with practically no additional mechanism over that required in reproduction.

It is another object of my invention to provide 40 an approved apparatus of this type by means of which a plurality of records may be reproduced either serially or simultaneously, as may be desired.

A further object of my invention is to provide 45 an improved apparatus of the type set forth in which the light beam, although maintained stationary, is, nevertheless, rendered effective at that portion of the sound track which it is desired to reproduce and at that portion only.

Still a further object of my invention is to provide 50 an improved apparatus of the type mentioned in which cross talk, or the simultaneous reproduction of two adjacent lines of the spiral, is entirely eliminated.

Another object of my invention is to provide 55

a novel scanning system for apparatus of the aforementioned type.

It is also an object of my invention to provide a method by which the proper location of the scanning means with respect to the record is insured.

And a further object of my invention is to provide improved apparatus of the type noted heretofore which will be exceedingly simple in construction and extremely simple in operation, which can be manufactured without necessity of observing fine tolerances, and which is not only very efficient in operation, but also extremely versatile in the results which it can produce.

According to my invention, I provide, in a phonograph employing a record on which the sound is recorded in the form of an Archimedian spiral track, a stationary light source and optical system which focuses a fine line of light radially across the record so as to include all the spirals or turns across one radius. On the other side of the record, a stationary photo-electric cell is disposed, the active element of the cell having a length equal to the length of the radial light line and being in alignment therewith. In order to mask off all the light except that desired at the reproducing point, an opaque mask provided with an Archimedian, transparent spiral is placed adjacent the record so that the spiral record track and the spiral in the mask will have the same geometrical center. The action will be readily understood upon considering the equation of an Archimedian spiral. It will be noted that the derivative in the radial direction is constant, that is, the rate of radius change is constant throughout the length of such a spiral. Taking advantage of this fact, it is possible to choose at least one such curve which, when rotated at some definite speed, will intersect another concentric Archimedian spiral rotated at some other speed along certain fixed lines in space lying in the plane of the spirals and passing through their common center. Now, if the line of light mentioned above is located at one of these fixed lines, that portion of the line of light which will pass through both the scanning mask and the record, and thus will reach the photo-electric cell, must move in a radial direction with a velocity equal to that of the record spirals in the same direction. By proper choice of the width of the scanning spiral and proper optical system design, light from the reproducer optical system can be prevented from passing through an adjacent record spiral to the photoelectric cell, and the possibility of cross talk is thus entirely eliminated. As for repetition of a single record or the reproduction of a plurality of individual records, either serially or simultaneously, this may be effected by proper choice of the number of scanning spirals and by the circumferential displacement and pitch of these spirals, while the control of the system to reproduce any preselected portion or portions of the record may be effected, for example, by control of the extinction lamp circuit.

The novel features that I consider characteristic of my invention are set forth with particularity in the appended claims. The invention itself, however, both as to its organization and method of operation, together with additional objects and advantages thereof, will best be understood from the following description of several specific embodiments thereof, when read in connection with the accompanying drawings, in which

Figure 1 is a central sectional view of one form of my improved apparatus.

Figure 2 is a plan view showing the relation of the record and the scanning mask, the record having a single spiral sound track thereon and the scanning mask having two scanning spirals thereon.

Figure 3 is a view similar to Figure 2 but showing the double-spiral scanning mask applied to a record having two sound tracks thereon.

Figure 4 is a perspective view of the reproducing optical system and its relation to the light source,

Figure 5 is a side or end elevation of a similar optical system arranged for recording,

Figure 6 is a view, partly in perspective and partly diagrammatic, illustrating one method of controlling the motor to stop it at a predetermined point in the record, and

Figure 7 is a view similar to Figure 6 but showing one method of controlling the light source filament circuit to insure reproduction of only a preselected portion of the record.

Referring, first, to Figure 1, there is shown a motor plate 1 on which is supported a motor 2 which drives a spindle 3 having a gear 4 fixed thereto. The gear 4 meshes with and drives a gear 5 to which is staked a gear 6 mounted for rotation on a stub shaft 7, the gear 6 meshing with and driving a gear 8 fixed to a sleeve 9 the upper end of which terminates in a flange 10. The gears 4, 5, 6 and 8 are so related that the sleeve 9 is rotated at considerably lower speed than the spindle 3 for a purpose that will herein-after appear, while a cover plate 11 serves to hide or cover these gears from view.

The sleeve 9 is rotatably mounted on a hollow shaft 12 which frictionally fits over the spindle 3 and which terminates in a central record receiving portion 13 at the upper end thereof beyond a flange portion 14 which acts as a record supporting turntable and lies in substantially the same plane as the flange 10. The sleeve 12 may be locked to the spindle 3 in any suitable manner for rotation therewith. In the particular embodiment illustrated, the spindle 3 is split at its upper end and is internally threaded below the split portion to receive a screw 15 having a wedge-shape head. As the screw 15 is screwed down, the wedge head expands the split portion of the spindle, thereby locking in place a record 16 supported on the flange 14.

The record 16 may comprise a disc of any suitable base, such as glass, celluloid, etc. coated with a photosensitive emulsion in which a sound track 17 has been recorded, the sound track being in the form of an Archimedian spiral of comparatively fine pitch and having, preferably, the same geometrical center as the disc itself. Mounted on the flange 10 is a disc of opaque material 18 having one or more Archimedian spiral scanning tracks 19 formed therein. By way of example, I have shown the scanning disc 18 as provided with two such spiral scanning tracks evenly spaced from each other circumferentially, but any number of scanning tracks may be employed as will appear more clearly hereinafter. The scanning disc 18 may be formed of some suitable opaque material such as metal, for example, in which case the scanning tracks 19 may be cut out or punched out therefrom to form transparent spiral scanning slots. The scanning disc 18 may, however, also be made of a photosensitized base similar to that of the record, with the scanning tracks recorded therein. In any case,

however, the scanning tracks 19 are made of a much coarser pitch than that of the sound tracks 17 and are also formed with their geometrical centers preferably coinciding with that of the disc 18.

- 5 The scanning disc 18 is mounted on the flange or turntable 10 and is fixed thereto by means of a pin 20, the axis of the scanning tracks 19 being in alignment with that of the spindle 3.
- 10 The record 16, as explained heretofore, is supported on the turntable 14 with the axis of the sound track 17 also in alignment with that of the spindle 3. Thus, the tracks 17 and 19 all have a common geometrical center when mounted on the phonograph for operation. The record 16 is also so mounted with respect to the scanning disc 18 that the beginning of the sound track 17 is in alignment with, or coincides with, the beginning of one of the spiral scanning tracks 19. For this purpose, the record 16 may be perforated with several apertures, each along a different radius from the center of the record. When the record 16 is placed on the turntable 14, these apertures are made to fit over a corresponding number of pins 21 upstanding from the turntable 14, the position of each of the apertures and their corresponding pins 21 being so chosen that the record 16 can only be mounted in operative position and locked to the turntable 14 when the beginning of the sound track 17 is in alignment with the beginning of one of the scanning tracks 19.

20 Fixed to the bracket 22 supported by the motor plate 1 is a casing 23 which houses a light source 35 and associated optical system for focusing upon the record 16 a thin line of light radially there-across and of such a length as to cover all of the turns of the sound track spiral along the radius. The light source may comprise a 30 straight coiled filament 24 (Figure 4) and the optical system a pair of cylindrical lenses 25 and 26. The lens 25 is disposed in close proximity to the filament 24 and has its axis at right angles to that of the filament, serving as a condenser 40 to produce a beam of minimum divergence after leaving the lens. A mask 27 may be provided to assist in limiting the field or area illuminated by the light passed through the lens 25. The lens 26 is placed as close to the record 16 as practical 45 with its axis parallel to that of the filament 24, and this lens serves to focus upon the record 16, in the plane thereof, the coil diameter of the filament 24. In this manner, maximum use is made of the light source and a fine or thin line 50 of light 28 is focused upon the record 16 across the sound track spiral 17.

55 Disposed beneath the scanning disc 18 in alignment with the light line 28 is a photoelectric cell 30 having an active element at least as long 60 as the light line 28 itself. Light passing through the record is modulated thereby and affects the photoelectric cell to cause it to set up varying currents representative of the sound being reproduced. The scanning disc 18 being opaque 65 except at the scanning tracks 19, it is apparent that light can pass through both the record 16 and the scanning disc 18 at only those portions where the sound track 17 and the scanning tracks 19 cross each other. Now, if the light line 28 is 70 focused upon the record in a position such that it intersects the sound track 17 and one of the scanning tracks 19 at the same point where these two tracks intersect each other, light will pass through both the record 16 and the scanning disc 18 at such point and at no other points.

75 Let it be assumed that the point where the sound track 17, the scanning track 19 and the light line 28 all intersect each other is at the beginning of the sound track, as shown in Figure 2, the scanning spirals 19 being in the "start" position designated S. As the record 16 rotates in the direction of the arrow, the spiral sound track 17 will move inwardly along the radial light line 28 at a rate depending upon the pitch of the adjacent turns of the sound track. For one revolution of the record 16, for example, the sound track 17 will have travelled along the radial light line 28 a distance equal to the pitch of the sound track spiral. In the same time interval, the scanning disc 18 must rotate through an angle such that the scanning track 19 under the light line 28 will also have moved along the light line the same radial distance, namely, a distance equal to the pitch of the sound track spiral. In other words, for one revolution of the sound record after starting reproduction, the scanning disc will have moved from starting position S to the position P, in which the active scanning track 19 will intersect the beginning of the second turn of the spiral sound track 17 20 immediately under the light line 28, and so long as this relation is maintained between the respective rotary speeds of the record and the scanning disc, the sound track 17 and its cooperating scanning track 19 will move along the fixed light 25 line 28 in overlapping or intersecting relation at the sound line. That is to say, as long as the aforesaid condition is maintained, the sound track 17 and one of the scanning tracks 19 will 30 always intersect each other at some point on the light line 28. It is for this reason that the sleeve 35 9 and the hollow shaft 12 are so geared together that the former rotates at a much slower speed than the latter.

35 The speed of rotation of the scanning disc 18 40 relative to that of the record 16 is determined by two factors, namely, the relative pitches of the sound track 17 and the scanning tracks 19, and the number of scanning tracks 19 on the disc 18. If the speed of the record is (θ) , for example, and the number of sound track spirals to be scanned is (y) , then the speed of the scanning disc must equal 45

$$\left(\frac{\theta}{y} \right)$$

50 where the scanning disc is provided with a scanning spiral of one revolution and which repeats the record immediately upon completing its first 55 playing. In other words, for a scanning disc having but one spiral in one revolution, the speed of the scanning disc will equal

$$\left(\frac{\theta}{y} \right)$$

60 and the pitch of the scanning spiral must be (y) times that of the sound track. Now, if the scanning disc is provided with (n) evenly spaced scanning spirals in one circumference of the scanning mask, it is clear that, for a record speed 65 (θ) , the scanning disc must rotate at a speed

$$\left(\frac{\theta}{ny} \right)$$

70 The gears 4, 5, 6 and 8 are so proportioned as to maintain the foregoing relationship between the speed of the sound record and that of the scanning disc, and in this way the active scanning spiral 19 and the sound track 17 are made to 75

travel uniformly inwardly along the fixed light line 28 in properly intersecting relation.

By proper choice of records having a plurality of sound tracks thereon and corresponding scanning discs, it is possible to employ the present invention for either the simultaneous reproduction of all the sound tracks or for successive reproduction thereof. For the sake of simplicity, suppose it is desired to reproduce either or both of two records recorded on the disc 16. Obviously, a portion of the radius could be allotted to each record and two scanning spirals of proper pitch could be located to embrace only these portions of the allotted radius. By the use of separate photoelectric cells, either record could be played individually or both records could be played simultaneously, depending, for example, on whether one or both photoelectric cells are energized. The optical system could be made to cover both records simultaneously, although, if desired, independent optical systems could be used for each record and the light source associated with each optical system controlled for either separate or simultaneous reproduction.

The same results can be accomplished by providing the record 16 with two concentric spiral tracks 17 and 17a as in Figure 3, each having twice the pitch of the sound track 17 of Figure 2, and both starting on the same diameter but at points on the circumference of the record 180° apart. For the sake of simplicity, I have shown a scanning disc having two spiral scanning tracks 19 and 19a associated with the record of Figure 3, the scanning track 19 cooperating with the sound track 17 and the scanning track 19a cooperating with the sound track 17a. Like the sound tracks 17 and 17a, the scanning spirals 19 and 19a are concentric and also start on the same diameter but 180° apart circumferentially of the scanning disc 18. The speed of the disc 18 must, in this case, be such that the complete record is played by one scanning track during half a revolution of the scanning disc and is repeated by the other scanning track during the next half revolution of the disc 18. By providing two optical systems to focus two light lines 28 and 28a onto the record 16 on opposite sides of the record center but on the same diameter and two photoelectric cells, the two sound tracks can be reproduced either simultaneously or separately, as desired.

It is also possible to employ my improved phonograph to effect the timing and occurrence of a certain number of events to synchronize with the record. For the sake of simplicity, and by way of example, I have shown, in Figures 6 and 7, how the stopping of the phonograph at a predetermined point may be effected or how only preselected portions of a record may be reproduced. Referring to Figure 6, I have shown a control ring 31 of conducting material which may be fixed to the gear 8 to rotate at the same speed as the scanning disc 18, the ring 31 being provided with an insulating block 32 at its periphery. A pair of brushes 33 and 34 connected in series with the motor 2 and a source of current supply contact the periphery of the ring 31 and complete the circuit to the motor therethrough. When, however, the insulating block 32 slides under the brush 34, the motor circuit is broken and the phonograph stops its operation. The block 32 may be set in the ring 31 at such a point, for example, that the phonograph will automatically stop at the completion of reproduction of a record and with the beginning of the

scanning track 19 in alignment with the beginning of the sound track 17 at the light line 28. A switch 36 connected across the brushes 33 and 34 may be used to start the phonograph again, or by maintaining the switch 36 constantly closed, continuous operation is assured. Obviously, instead of controlling the motor, the ring 31 may be employed to control the operation of any other device to cause the occurrence of some event related to the record.

In Figure 7, I have shown one method of effecting reproduction of only a preselected portion of a record. A control ring 41 similar to the ring 31 but stepped to provide two peripheral portions 42 and 43 is provided with a pair of insulating switch actuating members 44 and 45, the former on the periphery 42 and the latter on the periphery 43. The filament coil 24 is connected to a suitable source of current supply through a pair of switch contacts 46 adapted to be bridged by a contact member 47 the position of which is determined by a pair of relays 48 and 49. The relay 48 is connected to a source of current 50 through a master switch 51 and a spring blade switch 52 located in the path of travel of the actuating member 44, while the relay 49 is similarly connected to the source 50 through a master switch 53 and a spring blade switch 54 located in the path of travel of the actuating member 45.

As long as the motor 2 is energized, the ring 41, being fixed to the gear 8, for example, will continue to rotate indefinitely in the direction of the arrow and at the speed of the scanning disc 18. With the switch 51 closed, when the actuating member 44 rides under the blade of switch 52, the latter switch is closed momentarily whereupon the relay 48 is energized to move the contact member 47 into the solid line position of Figure 7, thus completing the circuit to the filament 24 and causing it to glow. The relays 48 and 49 may be holding relays or the contact member 47 may be of the toggle type. In either event, however, when the relay 48 has moved the contact member 47 to the solid line position, the contact member 47 will remain there and the filament 24 will continue to glow. With the ring 41 rotating in the direction of the arrow, the actuating member 45 will eventually close the switch 54. As soon as this occurs, the relay 49 is momentarily energized whereupon the contact member 47 is moved to and held in the dotted line position of Figure 7. This breaks the circuit of the filament 24 and reproduction stops. Thus, between the time that the actuating member 45 closes the switch 54 and the time that the actuating member 44 closes the switch 52, the filament 24 is not energized and therefore no reproduction takes place. By making the actuating members 44 and 45 respectively adjustable on the peripheries 42 and 43, the silent period can be controlled to omit any undesired portions of the record and, therefore, the phonograph set to reproduce only the preselected portion of the record. Also, by opening the switches 51 and 53, the control device may be rendered ineffective, and in such case, the contact member 47 may be operated manually. As in the case of the control system of Figure 6, that of Figure 7 may be employed to control the occurrence of any desired events or the operation of apparatus other than the filament 24 at a predetermined time and in synchronism with the record.

When it is desired to record sound, the reproducer may be readily converted into a re-

corder by simply inserting a light valve in the optical system. Such a light valve is shown diagrammatically at 60 in Fig. 5 and may comprise any one of the various forms of light valves well known in the prior art, as, for example, a Kerr cell, a pair of relatively movable shutters, or the like. The scanning disc 18 should then, of course, be on the same side of the record as the optical system.

10 Although I have shown and described several embodiments of my invention, it will be apparent to those skilled in the art that many changes therein and modifications thereof are possible without departing from the spirit thereof. For example, instead of mounting the record above the scanning disc, the latter may be mounted above the record, as shown in Figure 5. However, I prefer the construction shown in Figure 1, since it is usually necessary to change only the records. Mounting the record above the scanning disc permits making the scanning disc a permanent part of the apparatus, if desired. Many other changes will undoubtedly readily suggest themselves to those skilled in the art. My invention, therefore, is not to be limited except insofar as is necessitated by the prior art and by the spirit of the appended claims.

I claim as my invention:

1. In phonographic apparatus, the combination of a rotatable disc record, a rotatable record scanning member associated with said record, and a fixed optical system adapted to direct light toward said record and said scanning member.

2. In phonographic apparatus, the combination of a rotatable disc record, a record scanning member associated with said record and rotatable relative thereto, and a fixed optical system adapted to direct light toward said record and said scanning member.

3. In phonographic apparatus, the combination of a movable record having a spiral sound track thereon, and a scanning member associated with said record and movable relative thereto, said scanning member having a spiral scanning track thereon adapted to cooperate with said sound track to scan said sound track along its length as said scanning member is moved relative to said record.

4. The invention defined in claim 3 wherein the sound track and the scanning track are both Archimedian spirals of different pitches.

5. The invention set forth in claim 3 wherein the sound track and the scanning track are both Archimedian spirals and wherein the scanning track spiral has a greater pitch than the sound track spiral.

6. The invention set forth in claim 3 wherein the sound track and the scanning track are both Archimedian spirals and wherein the record and the scanning member are so associated that the sound track spiral and the scanning track spiral have a common geometrical center.

7. The invention set forth in claim 3 characterized in that the scanning member is associated with the record in a predetermined relation and characterized further by the addition of means for maintaining the record and the scanning member in said relation.

8. In photo-phonographic apparatus, a sound record, means for scanning said sound record, said sound record and scanning means being both movable relative to each other, means for providing a stationary light beam in cooperative relation to said record and said scanning means,

and means for maintaining said record and said scanning means in a predetermined movable relation to each other with respect to said light beam.

9. In photo-phonographic apparatus, the combination of a movable record having a spiral sound track thereon, an opaque scanning member associated with said record and movable relative thereto, said scanning member being provided with a transparent spiral scanning track, a light source, means for projecting from said light source a thin line of light radially across said sound track, and means for maintaining said sound record and said scanning member in such relation that said spiral sound track and said spiral scanning track will always intersect each other at some point on said line of light.

10. In photo-phonographic apparatus, the combination of a pair of concentric turntables, one of said turntables being annular and surrounding the other, a sound record supported on one of said turntables, said sound record having an Archimedian spiral sound track thereon, an opaque scanning member provided with an Archimedian, transparent, spiral scanning track, the pitch of said scanning track being greater than the pitch of said sound track, said scanning member being supported on the other of said turntables in a manner such that both said tracks have a common geometrical center, a light source, an optical system for projecting from said light source a thin line of light radially across said record, means for mounting said record on said first named turntable in a predetermined relation to said scanning member such that said sound track, said scanning track and said line of light all intersect at a point, means for rotating said record at a predetermined rotary speed, and means for rotating said scanning member at such a rotary speed relative to said record that said spiral scanning track will always intersect said sound track along said light line.

11. In photo-phonographic apparatus, the combination of a sound record having a plurality of sound tracks thereon, and a scanning member associated with said record, said scanning member having at least one scanning track for each of said sound tracks and being mounted for movement simultaneously with said record, and said scanning tracks being each adapted to scan the entire length of their respectively associated sound tracks.

12. In photo-phonographic apparatus, the combination of a movable sound record having a sound track thereon, and a scanning member associated with and movable relative to said record, said scanning member having a plurality of scanning tracks thereon each adapted to scan the entire length of said sound track, and the rate of movement of said scanning member relative to said record being a function of the number of scanning tracks on said scanning member.

13. In photo-acoustic apparatus, the combination of a rotatable sound record having a spiral sound track thereon, and a scanning member associated with and rotatable relative to said record, said scanning member being provided with a spiral scanning track of greater pitch than the pitch of said sound track, and the speed of rotation of said scanning member relative to that of the sound record being a function of the relative pitch dimensions of said respective tracks.

14. In photo-acoustic apparatus, the combina-

tion of a rotatable sound record having a spiral sound track thereon, and a scanning member associated with and rotatable relative to said record, said scanning member being provided with a plurality of spiral scanning tracks evenly spaced about the circumference thereof and of greater pitch than the pitch of said sound track, and the speed of rotation of said scanning member relative to that of the sound record being a function of both the relative pitch dimensions of said respective tracks and the number of scanning tracks on said scanning member.

15. In phonographic apparatus, a sound record, means for reproducing sound from said record, 15 and means external to the record for rendering said sound reproducing means ineffective to reproduce sound between predetermined points in said record.

16. In photo-phonographic apparatus, a photographic record, a light source adapted to cooperate with said record to reproduce sound, an energizing circuit for said light source, and means external to said record for maintaining said circuit closed between predetermined points in said record and open between other predetermined points in said record.

17. In photo-phonographic apparatus, a rotatable record having a spiral sound track thereon, a scanning member associated with said record and rotatable relative thereto, said scanning member having a spiral scanning track of greater pitch than said sound track for scanning said sound track, a motor for driving said record and said scanning member, and means for controlling said motor to cause it to stop when said scanning

member has reached a predetermined position relative to said record.

18. In photo-phonographic apparatus, a rotatable record having a spiral sound track thereon, a scanning member associated with said record and rotatable relative thereto, said scanning member having a spiral scanning track of greater pitch than said sound track for scanning said sound track, a motor for driving said record and said scanning member, and means for controlling said motor to cause it to stop when said scanning member has reached a predetermined position such that the beginning of its scanning track coincides with the beginning of the record track.

19. In photo-acoustical apparatus, means for illuminating a photographic record, said means comprising a filamentary light source, a cylindrical condensing lens in close proximity to the filament of said light source with the axis of said lens at right angles to that of said filament, and 20 a second cylindrical lens in close proximity to the record, said second lens having its axis parallel to that of said filament.

20. In photo-acoustical apparatus, means for illuminating a photographic record, said means 25 comprising a light source including a coiled filament, optical condensing means adjacent said filament for projecting toward said record a light beam of minimum divergence, and optical means adjacent the record for focusing upon said record, 30 in the plane thereof, the filament coil diameter.

21. In phonographic apparatus, the combination of a sound record, and scanning means therefor substantially co-extensive with the entire area of said record.

ELLSWORTH D. COOK.
